UNITED STATES PATENT OFFICE.

PETER HOBLE, OF CHICAGO, ILLINOIS.

DESIGN FOR A HOPPER FOR GRINDING-MILLS.

SPECIFICATION forming part of Design No. 18,629, dated September 25, 1888.

Application filed August 28, 1888. Serial No. 284,020. Term of patent 14 years.

To all whom it may concern:

Be it known that I, PETER HOBLE, of Chicago, in the county of Cook and State of Illinois, have invented and produced a new and useful Design for a Hopper for Portable Grinding-Mills, of which the following is a specification, reference being had to the accompanying drawing, forming a part thereof.

The figure in the drawing represents a perspective of my design, which consists of a hopper and supporting arm or bracket of the form shown.

My design consists in an inverted pyramidal-shaped hopper, A, and the supporting bracket-arm B, extending downwardly from said hopper.

The upper end of the bracket-arm B is bifurcated and embraces two sides of the hopper mounted thereon. The lower end of said arm is curved, as shown. 20

What I claim as new is

A design for a hopper for grinding-mills, consisting of an inverted pyramidal-shaped hopper, A, and the bracket-arm B, having the shape and configuration shown and described. 25

In testimony whereof I affix my signature in presence of two witnesses.

PETER HOBLE.
